(57) **CLAIM**

The ornamental design for a metal bottle, as shown and described.

DESCRIPTION

FIG. 1 is a front perspective view of the metal bottle;
 FIG. 2 is a front elevation view thereof;
 FIG. 3 is a top plan view thereof;
 FIG. 4 is a bottom plan view thereof;
 FIG. 5 is a front perspective view of a metal bottle according to an alternative embodiment;
 FIG. 6 is a front elevation view of the embodiment of FIG. 5;
 FIG. 7 is a top plan view of the embodiment of FIG. 5; and,
 FIG. 8 is a bottom plan view of the embodiment of FIG. 5. The broken lines in the drawings illustrate the portions of the metal bottle that form no part of the claim.
